ROBERT M. FRYER.

Improvement in Apparatus for Converting Reciprocating into Rotary Motion.

No. 124,805.

Patented March 19, 1872.

INVENTOR

UNITED STATES PATENT OFFICE.

ROBERT M. FRYER, OF NASHVILLE, TENNESSEE, ASSIGNOR OF ONE-HALF HIS RIGHT TO JOHN B. ROMANS, OF SAME PLACE.

IMPROVEMENT IN APPARATUS FOR CONVERTING RECIPROCATING INTO ROTARY MOTION.

Specification forming part of Letters Patent No. 124,805, dated March 19, 1872.

SPECIFICATION.

To all whom it may concern:

Be it known that I, ROBERT M. FRYER, of the city of Nashville, in the county of Davidson and State of Tennessee, have invented certain new and useful Improvements in Engine-Connections, of which the following is a specification:

Nature and Object.

The object of my invention is to produce a simple and practical combination of connections to convert reciprocating motion into continuous rotary motion; and this I accomplish by the use of a double-working beam or cross, one end (or arm) of which is connected with a crank, the opposite arm with a reciprocating cross-head, and the two remaining arms with separate reciprocating-pistons, by which means a reciprocating or vibrating, or both a vibrating and reciprocating, force is applied to the crank.

General Description with References to the Accompanying Drawing—

In which A A'' represent a vertical section of two cylinders, which are provided with pistons B B'', connected with rods C C''. D is a cross of four arms, E, F, G, and H. I I'' are vertical guides, for and between which cross-head J reciprocates. K is a crank, to which is connected E, (one of the cross-arms.) The opposite arm F is connected with cross-head J. Piston-rod C is connected with the cross-arm G by means of link L. Piston-rod C'' is connected with arm H by links L''. M, N, O, and P are the openings into the cylinders.

Operation.

When force is applied to either of the pistons separately the arm of the cross in connection therewith has a tendency to revolve the whole cross; but as this is prevented at the top by means of cross-head J, (which acts as a fulcrum,) the bottom or opposite arm is forced to the right or left, (as the case may be,) while at the same time it is forced in the opposite direction to the force applied to the

said piston when equal force is applied (in the same direction) to both pistons. The whole cross acts as an ordinary connecting-rod, in connection with a crank and reciprocating motion, inasmuch as it has no vibrating force. Now, by referring to the drawing it will be observed that the crank K is situated at the lower part of the cross D, and is placed at the upper extremity of its travel, and the pistons B B'' are at the upper end of their stroke. Steam being first admitted through opening M, the piston B is driven downward, and the crank K is moved in the direction of the arrow; and when said crank has traveled about forty-five degrees of a circle steam is admitted through opening N, which produces downward force upon piston B'', which, until then, has moved but a short distance. Both pistons now act together in forcing the crank around to about one hundred and thirty-five degrees from the starting point, when the pressure is relieved (or partially relieved) from the piston B, which at this time moves slow, and piston B'' is left to carry the crank around to one hundred and eighty degrees from the starting point, when steam is admitted through opening O, (the pressure from piston B'' being very soon after relieved,) which forces piston B upward, moving crank K in the direction of the arrow; and when said crank arrives at about two hundred and twenty-five degrees from the starting-point steam is admitted through opening P, which produces upward force at piston B'', (which, until then, has moved slow,) and thus both pistons are brought into action and carry the crank to about three hundred and fifteen degrees from the starting point, when the pressure is relieved, or partially relieved, from piston B, and piston B'' carries the crank up to the point from which the operation began.

It may be readily seen that the above combination will produce rotary motion with the steam-supply adjustment therein named, though in practice it may prove advantageous to vary this adjustment. It may be also stated, the position of the crank K and cross-head J may be reversed; or that all the present ver-

tical parts may be placed horizontally, and that a substitute may be employed in place of above-described cross; therefore

What I claim as my invention, and desire to secure by Letters Patent of the United States, is—

A cross or its equivalent, for the purpose of a connection between two reciprocating pis-

tons or their connections, a crank and a reciprocating cross-head or other suitable guide, combined substantially as and for the purpose above set forth.

ROBERT M. FRYER.
